UNITED STATES PATENT OFFICE.

SIEGMUND LOEWE, OF BERLIN, GERMANY, ASSIGNOR TO WESTERN ELECTRIC COMPANY, INCORPORATED, OF NEW YORK, N. Y., A CORPORATION OF NEW YORK.

AMPLIFYING SYSTEM.

Application filed March 19, 1921. Serial No. 453,844.

To all whom it may concern:

Be it known that I, SIEGMUND LOEWE, a citizen of the German Republic, residing at Berlin, Germany, have invented certain new and useful Improvements in Amplifying Systems (for which I have filed application in Germany, July 8, 1919, L-48522), of which the following is a full, clear, concise, and exact description.

10 This invention relates to amplifiers of the type employing space discharge devices having an anode, a cathode, and a controlling grid.

15 The amplifiers which have previously been used were constructed either for the amplification of high frequency currents, or for the amplification of low frequency impulses, but not for both.

20 The subject of the present invention is a simple universal amplifier which by virtue of its special construction is suited to the equally good amplification of any kind of electric impulse. High frequency and low frequency amplifiers have previously been 25 differentiated because it is difficult to bring low frequency impulses effectively to the amplifier without the intervention of iron transformers; while, on the other hand, the presence of iron transformers makes it impossible to bring high-frequency oscillations 30 to the amplifier. But it is possible to proportion a shunt with capacity, self induction, and resistance, such that this circuit forms a system whose impedance is independent 35 of the frequency. The shunt circuit consists of two branch circuits, one branch containing inductance and resistance, thus possessing inductive reactance, while the other branch contains capacity and resistance, thus possessing capacitative reactance. The conditions under which the impedance 40 of the shunt circuit is independent of the frequency are indicated by the following equation:

$$45 R_1 = R_2 = \sqrt{\frac{L}{C}} = Z,$$

50 where R_1 is the resistance of the inductive branch of the shunt circuit; R_2 is the resistance of the capacitative branch; L and C are the inductance and capacity respectively of the two branches; and Z is the impedance of the combination.

According to the invention such a system 55 is used to lead the energy to the universal amplifier.

The drawing shows the amplifier arranged in accordance with the invention.

1 and 2 are two connecting terminals of 60 the input circuit to which the impulses to be amplified are in some manner conducted. The network, or shunt 3, having an impedance which is constant for oscillations of all frequencies impressed thereacross, comprises 65 one branch containing capacity 6, in series with resistance 8, and a second branch containing an inductance element 7, containing inductance and resistance in series. One end of this shunt circuit leads to the cathode, 70 and the other to the electrostatic control element or grid of the first amplifier or repeater tube 4 of the space current type. Either an ohmic resistance 5 or a shunt similar to shunt 3 can be used for a coupling 75 between the tubes in the cascade arrangement shown. It is important that the impedance or ohmic resistance of system 5 should be selected equal or approximately equal to the internal resistance of tube 4; 80 since only with this condition can the best action be obtained. It will be noted that the grid of the second tube is conductively connected to the anode of the preceding tube. The other details of the figure are self-evident. There may be no special plate or anode battery, since the heating battery suffices as is possible with efficient tubes. Anode batteries 9 may be used if desired. The drawing shows only two tubes, although in 85 practice a larger number may be used.

90 One further detail should be mentioned: in case the last anode circuit is to contain a telephone receiver 10, it is advisable to so construct the shunt of capacity, self induction, and resistance, that the telephone 10 itself serves as the self induction of this loop circuit.

95 The amplifier as described by the present invention can be directly inserted in any 100 high frequency system, so that it acts as detector and makes the incoming signals directly audible; for this reason it is especially suited to reception in wireless telephony. Each tube then has a detecting and an amplifying action. The same amplifier can also be used to advantage as a speech amplifier of the common type since it gives an unusu-

ally clear speech rendition in the absence of resonance to any of the speech frequencies. The whole system is very simple and cheap as the complicated intermediate transformers of the usual low frequency amplifier are avoided.

What is claimed is:

1. A repeater of the space current type, having an electrostatic control element and an input circuit, and a network including shunt elements only and containing reactance and resistance in series, connected to said input circuit and having a substantially constant impedance for oscillations of all frequencies impressed upon said input circuit.
2. A repeater of the space current type, having an electrostatic control element and an input circuit, and a network of shunt elements only, including inductance and resistance in series, said input circuit, said network having a substantially constant impedance for oscillations of all frequencies impressed upon said input circuit.
3. A repeater of the space current type, having an electrostatic control element and an input circuit, and means including shunt elements only in said input circuit, one of said elements including capacity and resistance in series, said means having a substantially constant impedance for oscillations of all frequencies impressed upon said input circuit.
4. A repeater of the space current type, having an electrostatic control element and an input circuit, and means having only shunt elements, including inductance and capacity in series with resistance, in said input circuit, said means having a substantially constant impedance for oscillations of all frequencies impressed upon said input circuit.
5. A repeater of the space current type having an electrostatic control element and an input circuit, and means, comprising a single closed loop including resistance, inductance, and capacity in series, connected in said input circuit, said loop having a substantially constant impedance for oscillations of all frequencies impressed upon said input circuit.
6. A repeater of the space current type having an electrostatic control element and an input circuit, and a network in shunt to said input circuit comprising two parallel branch circuits, one of said branches containing inductance and resistance, and the other of said branches containing capacity and resistance, said network having a substantially constant impedance for oscillations of all frequencies.
7. A repeater of the space current type having an electrostatic control element and an input circuit, and a network in shunt to said input circuit comprising two parallel

branch circuits, one of said branches containing inductance, L , and resistance, R_1 , and the other of said branches containing capacity, C and resistance, R_2 , said inductances, capacities and resistances having values as given by the equation

$$R_1 = R_2 = \sqrt{\frac{L}{C}}$$

8. A repeater of the space current type, having an anode, a cathode, and a grid, and a network, containing shunt elements comprising reactances in series with resistances, connected between said cathode and said grid and having a substantially constant impedance for oscillations of all frequencies impressed between said grid and cathode.

9. A plurality of repeaters of the space current type connected in cascade, each of said repeaters comprising an anode, a cathode, and a grid, the grid of one repeater being conductively connected to the anode of the preceding repeater, and means, containing reactances and resistances in series therewith, connecting said first named grid to its corresponding cathode and having a substantially constant impedance for oscillations of all frequencies impressed across said means, and a resistance connecting said second-named grid to its corresponding cathode.

10. A plurality of repeaters of the space current type connected in cascade, each of said repeaters comprising an anode, a cathode and a grid, the grid of one repeater being conductively connected to the anode of the preceding repeater, and a network connecting said last-named grid to its corresponding cathode comprising two parallel branch circuits, one of said branches containing inductance, L , and resistance, R_1 , and the other of said branches containing capacity, C , and resistance, R_2 , said inductances, capacities and resistances having values as given by the equation

$$R_1 = R_2 = \sqrt{\frac{L}{C}}$$

11. In combination, a vacuum tube detector for detecting and amplifying high frequency waves, an output circuit therefore, containing a network having substantially the same impedance for the high frequency waves as for the detected waves, said network including the windings of a telephone receiver.

12. An amplifier of the three-electrode space current type, having an output circuit connected to an anode and cathode and an input circuit connected to a control electrode and said cathode, and a network, including a single closed loop containing reactance, connected in shunt to said input circuit, said network having substantially

constant impedance for all frequencies within the range including speech or radio waves, and a resistance in said output circuit of substantially the same impedance as the impedance of said tube between said anode and cathode.

13. In combination, a plurality of space discharge repeaters in tandem, input and output circuits for said repeaters, the input circuit of one repeater being connected to the output circuit of another repeater, and a network of substantially constant impedance for high and low frequency waves included in the input circuit of one of said repeaters, a similar network included in the

output circuit of one of said repeaters, one of said networks including the winding of a telephone receiver.

14. In an amplifier, a three-electrode space discharge tube, means connected to two electrodes of said tube having substantially constant impedance for high and low frequency waves, said means comprising an element including a capacity, and a second element in shunt to the first element including the windings of a telephone receiver.

In witness whereof, I hereunto subscribe my name this ninth day of February, A. D. 1921.

DR. SIEGMUND LOEWE.
